UNITED STATES PATENT OFFICE.

ADOLPH RUBIN, OF ST. LOUIS, MISSOURI, ASSIGNOR TO SIEBER PRODUCTS MFG. CO.,
OF ST. LOUIS, MISSOURI, A CORPORATION OF MISSOURI.

LOOSE-LEAF BINDER.

Application filed October 16, 1922. Serial No. 594,815.

To all whom it may concern:

Be it known that I, ADOLPH RUBIN, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same.

10 This invention relates to loose leaf binders of the type in which the leaves are retained in position by tapes, bands or cords that are connected to a winding shaft which is adapted to be rotated in one direction to draw the tapes taut, and thus cause the leaves to be clamped tightly between the two leaf clamping members of the binder.

One object of my present invention is to provide an efficient mechanism of novel design and inexpensive construction for locking the winding shaft of a loose leaf binder of the general type referred to.

Another object is to provide a loose leaf binder of novel construction that embodies the desirable features and characteristics of the loose leaf binder described in my U. S. Patent No. 1,271,228, dated July 2, 1918.

To this end I have devised a loose leaf binder that comprises a winding shaft and a locking mechanism for said shaft composed of a coiled spring which surrounds the shaft, and means for causing one or more coils of said spring to exert sufficient frictional pressure on the shaft to lock the same or prevent the shaft from accidentally turning in a direction to slacken or loosen the tapes. Said locking spring can be arranged in various ways and various means can be used for causing said spring to clamp and hold the winding shaft. In the form of my invention herein illustrated the locking spring is so constructed and arranged that when it is in its inoperative condition it will not interfere with the rotary movement of the winding shaft either forwardly or rearwardly, and when it is in its operative condition, it will securely hold the winding shaft against rotary movement rearwardly. The means that is used to cause the locking spring to engage and hold the winding shaft consists of an element that exerts pressure on said spring in a direction tending to twist the spring, and thus reduce the di-

ameter of one or more coils of same sufficiently to force said coil or coils into snug engagement with the shaft. Said element can be formed in various ways without departing from the spirit of my invention, but it preferably consists of a cam or inclined surface arranged in proximity to a lateral extension on one end of the locking spring and adapted to be engaged with said extension by moving one of said parts relatively to the other, so as to twist or turn the spring in a direction to draw one or more coils of the same tightly around the shaft, and thus bind or hold the shaft. When it is desired to release the winding shaft said cam or inclined surface is disengaged from the lateral extension on the spring, thereby permitting the spring to unwind or assume its former condition, namely, surrounding the shaft without exerting sufficient frictional pressure on same to hold it against rotary movement rearwardly.

Figure 1 of the drawings is an end elevational view of a loose leaf binder constructed in accordance with my invention showing the tapes of the binder tightened.

Figure 2 is a similar view, showing the tapes slackened.

Figure 3 is a top plan view of the binder, showing the tapes slackened and the locking spring on the winding shaft in its inoperative condition.

Figure 4 is a detail view, showing a portion of the winding shaft and the device that is used to move said shaft endwise of its bearings, illustrating said device in the position it occupies when the winding shaft is locked.

Figure 5 is a detail view of the parts shown in Figure 4, illustrating said parts in the position they assume when the winding shaft is released.

Figure 6 is a bottom plan view of a portion of the leaf clamping member that carries the winding shaft, showing the locking spring on the winding shaft in its operative condition.

Figure 7 is a cross-sectional view, taken on the line 7—7 of Figure 6, locking in the direction indicated by the arrows; and

Figure 7^a is a similar view, showing the locking spring on the winding shaft in its inoperative condition.

Referring to the drawings which illustrate the preferred form of my invention, A and A' designate two leaf clamping members between which leaves B are arranged. 5 C designates tapes or bands of flexible material that pass through slots in the leaves B, and D designates a winding shaft to which one end of the tapes C are connected, the other ends of said tapes being connected 10 to the leaf clamping member A'. The winding shaft D is rotatably mounted in bearings on the leaf clamping member A, and means is provided for locking, clamping or holding said shaft after it has been turned 15 in a direction to draw the tapes taut so as to cause the leaf clamping members A and A' to firmly clamp or bind the rear edge portions of the leaves together, as shown in Figure 1.

20 The means that is used for locking, clamping or holding the winding shaft D is of novel construction and is composed of a coiled spring E that surrounds the winding shaft, and means for causing said spring 25 to exert sufficient frictional pressure on said shaft to prevent it from turning accidentally. The spring E is preferably arranged between two of the shaft bearings 1 on the leaf clamping member A, and said spring 30 is provided at its opposite ends with lateral extensions 2 and 3 that bear upon opposite sides of a stop formed by the portion 4 of the leaf clamping member A that lies between the two shaft bearings 1 between which 35 the spring E is arranged. The spring E is so proportioned that when it is in its inoperative condition, as shown in Figures 3 and 7^a, the coils of same snugly surround the winding shaft D, without, however, exerting sufficient frictional pressure on same 40 to prevent the shaft from being rotated, and as the lateral extensions 2 and 3 at the upper and lower ends of the spring are positioned on opposite sides of the stop 4, rotary movement of the winding shaft in either direction has no tendency to tighten the spring or increase the frictional pressure of the coils of same on the winding shaft. Consequently, when the spring E is in its inoperative condition, the winding shaft is 45 free to turn forwardly to tighten the tapes or to turn rearwardly to slacken the tapes. The locking of the winding shaft is effected by exerting pressure on the lateral extension 2 at the upper end of the spring E in such a way as to slightly twist or tighten said spring, thereby reducing the diameter of one or more coils of the spring and causing the same to exert sufficient frictional 50 pressure on the winding shaft to tightly clamp the same and hold it against rotary movement either forwardly or rearwardly. In the form of my invention herein illustrated the means that is used to exert pressure on the extension 2 at the upper end of 55

60

65

the spring E consists of a cam or inclined surface 5 arranged on the stop or portion 4 of the leaf clamping member A in proximity to said extension 2, said cam or inclined surface 5 being so designed that when the extension 2 on the spring E rides up onto same, as shown in Figures 6 and 7, the upper coil or coils of the spring will be drawn so tightly around the winding shaft that it is impossible for said shaft to accidentally turn in either direction. In the form of my invention herein shown the cam 5 is formed by a pressed portion on the stop 4 of the leaf clamping member A, but it will, of course, be understood that the cam or inclined surface 5 can be formed in various other ways. 70

Various means can be used for moving the lateral extension 2 on the locking spring E into engagement with the cam 5, so as to render said spring operative for locking the winding shaft, but I prefer to equip the binder with a device F that is combined with the winding shaft D in such a manner that when said device F is moved in one direction, the winding shaft will move downwardly, longitudinally of its bearings, and thus compress the spring E in a direction to force the lateral extension 2 on same up onto the cam 5, and when said device is restored to its former position, the spring E will, expand, thereby moving the winding shaft upwardly and carrying the lateral extension 2 on the spring out of engagement with the cam 5. 80

As shown in Figure 3, the winding shaft is provided with a shoulder 6 that serves as an abutment for the upper end of the spring E, said spring being interposed between a washer 7 that bears against the underside of said shoulder and a washer 7^a that bears against the shaft bearing 1 located directly underneath the spring E. The winding shaft is provided at its lower end with an abutment 8, rigidly secured to said shaft and provided with a pair of oppositely-disposed notches 9 that receive trunnions 10 on the device F previously referred to. Said trunnions 10 are so formed that when the device F is turned into a horizontal position, as shown in Figure 4, the trunnions 10 will exert downward pressure on the abutment 8 on the lower end of the winding shaft, thereby causing said winding shaft to move downwardly longitudinally of the bearings on the leaf clamping member A in which said shaft turns. When the device F is thereafter restored to its former vertical position, as shown in Figure 5 and in Figure 3, the winding shaft will move upwardly relatively to its bearings, due to the expansive force of the spring E, the trunnions 10 on the device F being so designed that when the device F is in its vertical position, the upper ends of said trunnions 90

100

110

120

140

- will extend substantially flush with the upper end of the abutment 8 on the winding shaft in which said trunnions turn. If desired, a washer 11 can be interposed between the abutment 8 on the winding shaft and the bottom shaft bearing on the leaf clamping member A, so as to form a wearing surface or bearing face for the trunnions 10. I also prefer to interpose a sliding abutment member 12 between the upper end of the spring E and the washer 7 and provide said sliding abutment member with a notch, as shown in Figures 7 and 7^a, that receives the vertically-disposed stop portion 4 on the leaf clamping member A, so as to reduce any tendency of the locking spring E to twist or turn in a direction to lock the winding shaft when said spring is in its inoperative condition, namely, with the extension 2 at the upper end of same out of engagement with the cam 5.
- A loose leaf binder of the construction above described is of such simple design that it is not apt to get out of order; it can be manufactured at a low cost and the locking means for the winding shaft is easy to operate and eliminates the possibility of the winding shaft turning accidentally in a direction to slacken the tapes.
- Having thus described my invention, what I claim as new and desire to secure by Letters Patent is:
1. A loose leaf binder, comprising a winding shaft, a coiled spring surrounding said shaft, and means for causing said spring to exert sufficient frictional pressure on the shaft to lock the same or hold it against rotary movement.
  2. A loose leaf binder, comprising a winding shaft, a coiled spring surrounding said shaft, and means for drawing one or more coils of said spring into sufficiently snug engagement with the winding shaft to prevent same from turning accidentally.
  3. A loose leaf binder, comprising a winding shaft, a coiled spring surrounding said shaft, and means for twisting or turning said spring so as to cause one or more coils of same to exert sufficient frictional pressure on the shaft to prevent it from turning accidentally.
  4. A loose leaf binder, comprising a winding shaft, a coiled spring surrounding said shaft, and means for exerting pressure on said spring in such a way as to reduce the diameter of one or more coils of same and thus cause the spring to hold the winding shaft against rotary movement.
  5. A loose leaf binder, comprising a winding shaft, a locking member through which the winding shaft extends, and means for drawing said locking member into sufficiently snug engagement with the winding shaft to lock and hold the same.
  6. A loose leaf binder, comprising a wind-
- ing shaft, a resilient locking member through which said shaft extends, and means for reducing the internal diameter of said locking member so as to cause the same to hold the shaft against rotary movement.
7. A loose leaf binder, comprising a winding shaft, a spring surrounding a portion of said shaft and provided with a lateral extension, and a part that is adapted to engage said extension and exert pressure on said spring in a direction to cause the same to hold the shaft against rotary movement.
8. A loose leaf binder, comprising a winding shaft, a spring surrounding said shaft, a device that is adapted to engage said spring and exert pressure on same in a direction to cause the spring to hold the shaft against rotary movement, and means for effecting the engagement and disengagement of said co-operating elements.
9. A loose leaf binder, comprising a winding shaft, a coiled spring surrounding said shaft and provided with a lateral extension, a part that is adapted to engage said extension and twist said spring so as to cause the same to hold the winding shaft against rotary movement, and means for effecting the engagement and disengagement of said extension and part, for the purpose described.
10. A loose leaf binder, comprising a winding shaft, a coiled spring surrounding said shaft and provided with an extension, a cam that is adapted to engage said extension and twist or turn the spring, and means for moving said extension up onto said cam.
11. A loose leaf binder, comprising a winding shaft, a coiled spring surrounding said shaft and provided with a lateral extension, an inclined surface arranged in proximity to said extension, and means for compressing said spring endwise so as to cause said extension to engage said inclined surface.
12. A loose leaf binder, comprising a winding shaft, a support for said shaft in which said shaft can move endwise, a coiled spring surrounding said shaft and provided with a lateral extension, an inclined surface that is adapted to be engaged by said extension, for the purpose described, and means for moving said shaft endwise of its support so as to cause the extension on said spring to engage said inclined surface.
13. A loose leaf binder, comprising a winding shaft, a bearing in which said shaft turns, a coiled spring surrounding said shaft between said bearing and a shoulder on the shaft, a lateral extension on said spring, a part that is adapted to co-operate with said extension to cause the spring to hold the shaft against rotary movement, and means for moving said shaft endwise of said bearing.

ing so as to compress the spring and force the extension on same into engagement with said part.

14. A loose leaf binder, comprising a winding shaft, a member in which said shaft is rotatably mounted, a coiled spring surrounding said shaft between a shoulder thereon and a bearing on said member, a lateral extension on one end of said spring,

an inclined surface on said member arranged in proximity to said extension, an abutment member on said shaft, and a device interposed between the abutment member on the shaft and the member in which the shaft turns for exerting an endwise thrust on said shaft, for the purpose described. 10 15

ADOLPH RUBIN.
